UNITED STATES PATENT OFFICE.

FREDERIC R. H. THOMAS, OF HUDSON, NEW YORK.

SODA-WATER APPARATUS.

SPECIFICATION forming part of Letters Patent No. 312,588, dated February 17, 1885.

Application filed May 12, 1884. (No model.)

To all whom it may concern:

Be it known that I, FREDERIC R. H. THOMAS, a citizen of the United States, and a resident of Hudson, in the county of Columbia and State of New York, have invented certain new and useful Improvements in Mineral-Water Apparatus, of which the following is a specification.

My invention relates to apparatus in which mineral waters and like beverages are mixed and impregnated with carbonic-acid gas, and while so impregnated are bottled. For this purpose the gas under pressure from a gasometer and the water from a separate reservoir are admitted simultaneously by separate pipes into a pump, by which they are fed into a fountain, where they are kept in commotion by a revolving dasher or agitator, and are thence drawn off into bottles; but in similar apparatus as heretofore constructed the agitator, acting in one direction only, moves the liquid with it like a revolving cylinder of water, thereby causing the gas to impinge upon and be carried round with the surface of such revolving water-cylinder without permeating the entire mass, and to be concentrated or collected mainly above the liquid in the fountain, thence to return to the gasometer, while the liquid becomes comparatively "flat." Another objection is that the pump during the downward or feeding stroke of its piston receives air, which leaks in through the stuffing-box and gradually works its way into the liquid and gas, thereby also rendering the beverage what is termed "flat."

My invention has for its object to obviate the said defects, and it comprises the construction and combination, with a gas and liquid mixing fountain, of an agitator of two or more parts revolving separately in opposite or contrary directions, thereby producing a thorough mixture of the gas and liquid; also, the combination, with the pump-cylinder space between the stuffing-box and piston, of a displaceable column of water forming a water-seal to prevent the entrance of air, as will be hereinafter described and claimed.

In the accompanying drawings, Figure 1 represents an end elevation of a mineral-water apparatus for bottlers' use, improved according to my present invention. Fig. 2 is a

side elevation of the same, or as seen in the direction of arrow 1 of Fig. 1. Fig. 3 is a longitudinal vertical section of one of the fountains, showing the construction of the agitator. Fig. 4 is a cross-section on the line *x x* of Fig. 3, seen in the direction of arrow 2.

A is the frame of the machine, in which are located at opposite sides of and parallel with a centrally-working shaft, *B*, two fountains, *a*. The shaft *B* is provided with a pulley, *C*, through which and a belt motion is transmitted to it from an engine or other motor. It also has a fly-wheel, *D*, and at opposite ends pulleys *E E'* and *F F'*, from which motion is transmitted to the agitators of the two fountains, the said belt *G* and the crossed belt *G'* transmitting motion to the agitator of the fountain at the left side, (looking at Fig. 1 at the left side,) and the crossed belt *H* and the straight belt *H'* transmitting motion to the agitator of the fountain at the right side. The belts *G H'* are dotted in Fig. 1, in order to better distinguish them from the other belts.

The fountains being alike, a description of the one on the right will apply to the one on the left side.

I are the ordinary glass gages, and *i* the pressure-gages. The liquid to be charged with carbonic-acid gas is drawn from its proper tank or reservoir by means of the pump *b* through the pipe *c*, and gas from the gasometer through the pipe *d*. The gas and liquid through the pipes *d c* are discharged from the pump into the fountain by means of a pipe, *e*. The pump-piston receives its motion from the shaft *B* by an eccentric, *L*, in the usual manner.

In pumps as heretofore constructed for this purpose air gradually leaks in through the stuffing-box of the piston on the downward or feed stroke of the piston, and gradually works its way into the mixed liquid and gas discharging into the fountain, thereby causing the beverage to become more or less flat. To remove this objection I provide a pipe, *f*, leading from some sufficiently-elevated reservoir, or otherwise arranged, so as to keep a moderate degree of pressure at the lower end of the pipe, which is inserted below the stuffing-box of the pump, and above the piston, or about where shown in Fig. 2, in such a manner that water in the said pipe *f* will always stand above the

piston, thereby making a water-seal between the same and the stuffing-box, which effectually prevents the aforesaid leakage of air.

The ordinary four-way discharge to fillers for filling bottles is designated by the letter *g*, and the discharge-pipe from the top of the fountain for conveying back to the gasometer the surplus gas, so as to use it over again when needed, is designated by the letter *h*. The fountain *a* is made in two parts having flanges, as usual, by which they are bolted together at the middle or end, as shown in the drawings; but in filling fountains as heretofore used the agitator is moving in one direction only, thereby acting defectively and mixing imperfectly, for the reason stated in the preamble of this specification. In order to remedy this, I provide an agitator of two parts or frames, *j k*, one arranged inside of the other, the outer frame, *j*, having centrally-projecting fingers, *m*, and the inner part of the frame *k* having radially-projecting fingers *n* placed alternately at right-angles or at an angle to each other intermediate to the said fingers *m*, so that when the frames are revolved in opposite directions the fingers *n* will revolve in the spaces between the fingers *m*. The shafts or journals *K J* of the frames *k j* have their bearings and stuffing-boxes through the opposite ends of the fountains, and are provided with pulleys *M N* to receive the aforesaid belts *H' H*, respectively, the inner end of the shaft *K* having its bearing in an end hub, *O*, in the frame *j*, and the frame *j* having the bearing of its opposite end upon the shaft of the frame *k*, the bearing being formed by brasses and caps *P*, as shown in Figs. 3 and 4. Since the belt *H*, which communicates its motion from the shaft *B* to the pulley *N*, is crossed, and the belt *H'*, which communicates motion from the same shaft to the pulley *M*, is straight—that is, not crossed—it is evident that the said pulleys *M N*, and thereby the shafts *K J* and the frames *k j*, must

revolve in opposite directions, thus causing a thorough commotion of the liquid and a thorough intermixture of the same with the gas, thereby producing a superiorly-charged beverage, which is drawn out into bottles during the operation of the apparatus in the usual manner.

I do not claim, broadly, a dasher of two parts moving in opposite directions, for such, I am aware, has been used in churning, an instance of which may be found in United States Patent No. 150,734.

Having thus described my invention, I claim as new and desire to secure by Letters Patent—

1. In a fountain for mixing together compressed gas and liquid, the combination of the agitator-frames *j k*, provided with alternately-arranged fingers *m n*, substantially as described, the said frame *j* being journaled with its outer end through one end of the fountain, and with its inner end upon the shaft *K* of the frame *k*, and the said frame *k* being journaled with its outer end through the opposite end of the fountain, and with its inner end in an axial socket of the frame *j*, and the oppositely-projecting journals being provided outside of the fountain with end pulleys, *N M*, or their equivalents, for communicating opposite rotary motion to the said frame, as hereinbefore set forth.

2. The combination, with a feed-pump to a gas and liquid mixing fountain, of a pipe, *f*, entering the pump-cylinder between the stuffing-box and piston for maintaining a column of liquid above the piston, for the purpose set forth.

In testimony that I claim the foregoing as my invention I have signed my name, in presence of two witnesses, this 28th day of April, 1884.

FREDERIC R. H. THOMAS.
